TUBULAR HAIR CURLER WITH OPENINGS
AND PROTRUSIONS THEREABOUTCharles F. Hutcheon, Roslyn Heights, N.Y., assignor to
Forest Plastics, Inc., Westbury, N.Y.
Filed Apr. 14, 1966, Ser. No. 542,629
2 Claims. (Cl. 132—40)

This invention relates to hair curlers in general and in particular to tubular hair curlers having a plurality of outwardly directed hair-gripping projections.

10 Curlers are used by women to achieve a wave in their hair where a natural wave either does not exist or where its appearance is dictated by current fashion. A tuft of hair is moistened and is wrapped around the curler. Upon drying, the hair shrinks and assumes a wavy form. Many hair curlers of different sizes, shapes and function are currently available. Some of the prior art hair curlers that are known to structurally approximate the present invention will now be briefly described.

The present invention requires none of the assembly steps essential to the prior art. A plastic material such as polypropylene, cellulose acetate, polyethylene or cellulose butyrate, is extruded in the form of a thin-walled tube. As the tube comes from an extruder it is perforated by radially positioned harpoons. Upon entering the wall of the tube, the harpoons form the apertures and also tear the material in several places about the periphery of the aperture to define petals. When the harpoons are withdrawn, some material is pulled outwardly to define exposed edges on the petals. Axial movement of the extruded tube may be employed to drive the harpoons into and out of the wall of the hair curler, so that auxiliary drive means for the perforating devices is not necessarily required.

15 The perforations formed by the harpoons are petal-shaped, and extend radially outward from the outer surface of the hair curler body. Each aperture so formed is defined by a number of ridgelike segments. Usually two to four petals are formed, so that there are four to eight hair-engaging surfaces. The apertures are formed continuously at the same rate as the tube is being extruded. Therefore, complicated timing mechanisms are not required.

In view of the foregoing, it is an object of this invention to provide an improved plastic hair curler.

20 It is another object to provide a low cost hair curler having a plurality of hair-gripping protrusions formed on the outside surface thereof.

A further object is to provide a hollow, thin-walled hair curler having uniformly placed apertures and hair-gripping protrusions positioned about the apertures.

25 These and other features, objects and advantages of the invention will, in part, be pointed out with particularity and will, in part, become obvious from the following more detailed description of the invention taken in conjunction with the accompanying drawing which forms an integral part thereof.

In the various figures of the drawing like reference characters designate like parts.

In the drawing:

30 FIG. 1 is a side elevation of a hair curler embodying the features of this invention;

FIG. 2 is an end elevational view of the hair curler shown in FIG. 1;

35 FIG. 3 is a perspective view of a typical aperture formed in the wall of the hair curler;

FIGS. 4 and 5 are typical plan and sectional elevational views, respectively, taken through one of the apertures in the hair curler wall;

40 FIG. 6 is a schematic side elevational view of the apparatus used in the method comprising this invention;

2

FIG. 7 is a transverse sectional view taken along line 7—7 of FIG. 6;

FIG. 8 is another transverse sectional view taken along line 8—8 of FIG. 6;

5 FIG. 9 is an enlarged detail view of a typical perforating wheel; and

FIG. 10 is an enlarged view of the perforating means used with this invention.

Referring now to the drawing and in particular to FIGS. 1—5, it will be seen that hair curler 10 is comprised of a tubular body portion 12. A plastic material such as polyethylene, polypropylene, cellulose acetate or cellulose butyrate, has been found convenient to use, since it may readily be extruded. The body portion of the hair curler is provided with a number of longitudinal rows of perforations 14. In the embodiment illustrated there are eight rows, but it should be clearly understood that more or less rows may be used depending upon the diameter of the curler and the number of holes desired.

20 Perforations 14 are clearly shown in FIGS. 3, 4 and 5. Therein it may be seen that each perforation or aperture is comprised of a plurality (four are illustrated) of petals 16, each having ridgelike edges 18. When the hair is wound on the curler, the ridges will snare the hair as it is being wound and will securely hold the hair to the curler body.

25 The method of forming the hair curler described above is shown in FIGS. 6—10. Conventional extruding apparatus 20 delivers a tubular length of plastic material first to a cooling tank 21 and then to the perforating heads 22a and 22b. In the embodiment illustrated the perforating means are comprised of a number of wheels 24 angularly and axially spaced from each other. In FIGS. 7 and 8 particularly, it may be seen that the wheels are angularly displaced from each other by an arc of 45°. For convenience the wheels are illustrated in two axially separated banks, although it should be understood that the wheels may all be in one bank. The wheels in each bank, as illustrated, are 90° apart from each other, and the banks are out of phase with each other by a 45° angle. Suitable shaft means 26 are used to rotatably journal the wheels in the perforating heads. It is also within the scope of this invention to have all the wheels geared together. Furthermore, it is within the scope of this invention to provide means for radially adjusting the position of the wheels to accommodate different diameter hair curlers.

30 The periphery of each wheel is provided with a number of radially oriented harpoons 28 as shown in FIGS. 9 and 10. It is contemplated that the harpoons be radially adjustable within each wheel as an alternative to radially adjusting the position of the wheels as described above. The harpoon has a sharply pointed outer end 30 and a transverse face 32 inward of the pointed end. The transverse face is joined to the body portion 34 of the harpoon by a short, tapered section 36. Thus as the pointed end of the harpoon enters the wall, an aperture will be formed therein. The harpoons pierce the wall at least to the depth of the transverse face thereof. This usually tears the material around the aperture to define several petals. When the harpoon is withdrawn the transverse face tends to pull the material outwardly about the aperture to form the petals 16 and ridges 18, shown in FIGS. 3, 4 and 5.

35 It is particularly noteworthy that auxiliary means for driving the perforating apparatus is not required. The tube is axially pulled from the extruding apparatus by the extrusion takeoff and, as it passes the perforating means, will cause rotation of the harpoon-containing wheels. In effect, the extruded tube drives the wheels. Continued movement of the tube after a particular harpoon has been driven through the wall cause the wheels

to rotate whereby the harpoon is withdrawn and the next harpoon is inserted.

Although not specifically illustrated, it is to be understood that the concept of this invention includes the use of perforating means other than the harpoons described. For example, the curler could be pressed against an internal cylinder having radially extending needles. Alternatively, an expandable collet having radially extending needles could be used to form the perforations. Regardless of the structure used, the essential feature of this 10 invention is that petals having ridge-like hair engaging edges are formed about each aperture. Accordingly, it is apparent that existing apparatus that is adapted to punch holes in hair curlers may be used provided means such as harpoons, needles, etc. are included for forming the petal-shaped apertures with hair gripping ridges.

The hair curler, by virtue of its plastic construction, is lightweight and may be worn in comfort. It is substantially non-deformable so that the hair may be tightly wrapped thereabout. The hair curler may be formed at 20 very limited additional expense inasmuch as complicated driving and timing means are not required for the perforating apparatus. The formation of the apertures and ridges is continuous at the same speed as the extrusion process. As the hair is wound on the curler body the ridges defined by the sides of the petals grip the hair.

Having thus disclosed the best embodiment of the invention presently contemplated, it is to be understood that various changes and modifications may be made by those skilled in the art without departing from the spirit 5 of the invention.

What is claimed is:

1. An improved hair curler comprising:

(a) a tubular body member having a plurality of apertures formed in the wall thereof;

(b) at least two petals positioned about each of the apertures, said petals extending from the outer surface of said body member, each of said petals being defined by irregular edges.

2. The device in accordance with claim 1 wherein said 15 body member is substantially non-deformable.
